STARTING DEVICE FOR FLYING-MACHINES.

1,024,429.

Specification of Letters Patent.

Patented Apr. 23, 1912.

Application filed July 27, 1911. Serial No. 640,778.

To all whom it may concern:

Be it known that I, KARL VÖLLER, a subject of the German Emperor, and resident of 12 Scharnhorststrasse, Dusseldorf, Germany, have invented certain new and useful Improvements in Starting Devices for Flying-Machines; and I do hereby declare the following to be a full, clear, and exact description of the invention, such as will enable others skilled in the art to which it appertains to make and use the same.

The present invention relates to a starting device for flying machines consisting in an arrangement of devices on the machine by means of which at the moment of starting the latter is raised from the ground so that all friction due to contact with the ground is eliminated.

According to the invention the starting device acting on the flying machine is connected with a boat pivotally suspended from the flying machine, so that the rising by means of the starting device can be effected either on land or on water.

The invention is illustrated in the accompanying drawings, wherein—

Figure 1 is a side elevation of a flying machine with the device in the position which it has before the rising action, Fig. 2 a like view with the device in the position which it has after the rising action, while Figs. 3, 4, 5 and 6 show details.

In the construction shown the starting device is such that the flying machine is launched by an explosion of powder. For this purpose there is an explosion chamber *a* (Figs. 1, 2 and 4) in the head of which is a charge of powder *b*. This small chamber carrying the charge is closed by a screw *c*, which carries an igniting device *d* of any suitable construction. Two pipes *e* connect the explosion chamber *a* with cylinders *f* respectively, which are pivoted to the flying machine one on each side thereof at *g*. In the drawing only one cylinder *f* is visible, since the second cylinder on the other side is behind the first and is hidden there. In each cylinder *f* there is a hollow piston rod *h* (Figs. 1, 2 and 3) having a piston *i*. The outer end of the piston rod is pivoted at *k* to the boat *l* which is suspended from the flying machine by parallel rods *m*.

In the position of rest the flying appa-

ratus has the position shown in Fig. 1 relative to the boat. The piston rods *h* are 55 pressed into the cylinders *f* by springs *n* (Fig. 3). Moreover, bolts *o* are inserted in the deck of the boat, and are pressed downward by the weight of the flying machine against the action of springs *p*. When the 60 flying machine is to rise, the charge of powder is ignited by the firing device. The powder gases pass through the pipes *e* into the cylinders *f* and expand therein and also in the bore of the piston rod *h*. In this manner the piston rods *h* are pressed forcibly downward and the boat is pressed firmly 65 against the ground or on to the surface of the water. The cylinders *f* are inclined at a certain angle to the horizontal. The force 70 is therefore exerted in this direction and gives a vertical and a horizontal component. Since the ground or water offers resistance to the boat *l*, which resistance against horizontal movement may be increased by spurs 75 *q* normally folded against the under surface of the boat, the flying machine is raised into the position shown in Fig. 2 by the action of the powder gases, and at the same time receives an impulse forward, which 80 added to the power of the motor gives the flying machine the necessary speed for flying. The launching of the flying machine is also aided by the springs *p*.

Having thus described my invention and 85 the best means I know of carrying the same into practical effect, I claim:—

1. In a flying machine, a starting device carried by the flying machine, a boat pivotally suspended from the flying machine 90 and between which latter and the boat there is a relative movement in starting, and means forming a pivotal connection between the starting device and the boat.

2. In a flying machine, a starting device 95 carried by the flying machine, a boat, links pivotally suspending the boat from the flying machine and between which latter and the boat there is a relative movement in starting, and means forming a pivotal connection 100 between the starting device and the boat.

3. In a flying machine, a starting device carried by the flying machine, a boat pivotally suspended from the flying machine 105 and between which latter and the boat there

- is a relative movement in starting, means forming a pivotal connection between the starting device and the boat, and folding spurs on the under side of the boat.
- 5 4. In a flying machine, a starting device carried by the flying machine, a boat pivotally suspended from the flying machine and between which latter and the boat there is a relative movement in starting, a pivotal connection between the starting device and the boat, and spring bolts on the boat adapt-
- 10

ed to be under compression when the flying machine is at rest and to assist the launch of the machine.

In testimony whereof, I have signed this 15 specification in the presence of two subscribing witnesses.

KARL VÖLLER. [L. S.]
